UNITED STATES PATENT OFFICE.

RICHARD H. MARVIN, OF EAST LIVERPOOL, OHIO, ASSIGNOR TO THE R. THOMAS & SONS COMPANY, OF EAST LIVERPOOL, OHIO, A CORPORATION OF OHIO.

HIGH-VOLTAGE SWITCH.

Application filed June 1, 1921. Serial No. 474,056.

To all whom it may concern:

Be it known that I, RICHARD H. MARVIN, a citizen of the United States of America, residing at East Liverpool, in the county of Columbiana and State of Ohio, have invented certain new and useful Improvements in High-Voltage Switches, of which the following is a specification.

My invention relates to high voltage switches, and particularly to a disconnecting switch for power lines of one hundred thousand or more volts. The object of my invention is to provide a switch of improved construction capable of handling a current of such high voltage.

In the accompanying drawings—

Fig. 1 is an end elevation of a switch tower and switch in which my invention is embodied in one form;

Fig. 2 is a side elevation thereof;

Fig. 3 is a broken side elevation of the switch terminals in the closed position of the switch, and drawn to a larger scale;

Fig. 4 is a section on the line 4—4, Fig.

25 3; and

Fig. 5 is a broken side elevation at right angles to Fig. 3, showing the switch contacts open.

An installation for a switch of the present type comprises a structural tower 6, to the head of which at 7 are connected strain insulators 8 and 9 with associated cable clamps 10 and 11, by which the power cable 12 is supported from the insulators. In the present installation, which is designed for a three-phase circuit, the tower structure comprises three such units, the unit 6 being supplemented by like units 13 and 14, as indicated in Fig. 2.

Instead of a jumper loop between the clamps 10 and 11, one end 15 of the cable is provided with a terminal 16 adapted to be connected to the stationary contact of the present switch, while the other end 17 of the cable, which is also provided with a terminal 18, is adapted to be connected to the movable contact of the switch. In view of the length of the end 17, which is connected to the movable contact of the switch, I prefer to provide it with some means to prevent its lateral swaying in the wind, and for this purpose I have here indicated a weight 19 secured to the cable end at such point that the vertical play of the switch contact end of the cable is not impeded.

Supported below the head of the tower is a multi-unit post insulator 20, to the bottom pin 21 of which (Figs. 3 to 5) is secured the fixed contact 22 of the switch. A second post insulator 23, mounted on a vertically movable plunger 24, has attached to the cap 25 of the top unit the movable switch contact 26. In the form here shown, the fixed contact 22 comprises a pair of brushes, between which the movable switch contact 26 enters and is engaged with an appropriate wiping contact. As here indicated, the contacts 22 and 26, respectively, are mounted in suitable screw bases 27 and 28, beneath which the terminals 16 and 17 of the power cable are gripped when the contact bases 27 and 28 are screwed into their respective post or cap supports on the insulators 20 and 23. Any other suitable means may be provided for establishing electrical connection between the cable ends and switch contacts, that shown being merely an illustrative installation.

I have also indicated a hood 29, supported by the contact base 27 and surrounding the fixed contact 22, so that in the closed position of the switch the contacts are housed against snow, rain, sleet, etc. The hood 29 performs the further function of serving as an arcing terminal on the opening of the switch, and also to prevent corona formation at the contact. It cooperates with an arcing ring 30 carried by cap 25 and surrounding the movable contact 26.

The plunger 24 on which the insulator 23 is supported, may be vertically moved by any suitable means. I have here indicated a pair of cross beams 31 and 32 through which the plunger passes, and by which it is vertically guided to maintain the precise alignment of the insulators 20 and 23 on the opening and closing movements of the switch. At the lower end of the plunger is pivoted a link 33 jointed to a toggle arm 34 fast on the shaft 35, which is supported in brackets 36 on the foot piece 37 of the tower structure, and extends longitudinally thereof a sufficient distance to serve the three switches simultaneously. On the shaft is a worm wheel 38 meshing with a worm 39, which may be rotated by a hand crank 40, or other suitable means. The weight of the several movable posts 23, and their associated mechanism, may be counterweighted at 41 to ease the operation of the

hand crank 40. As will be noted, the joint 42 between the arms 33 and 34 of the lifting and lowering toggle is located a trifle over center in the closed position of the switch, and is thus self-sustaining in closed position without strain on the lifting and lowering gear.

It will be noted that by mounting the switch contacts at the adjacent ends of the 10 pair of aligned post insulators, one of which is vertically reciprocated, there is no side strain on the insulator posts, and the latter are subjected only to compression strains. This is quite readily taken care of and affords no mechanical difficulties such as are 15 presented where insulators of this type are subjected to lateral thrusts. The construction as a whole is rigid, while at the same time simple and efficient. It will of course 20 be understood that a switch of this type is not primarily designed for breaking the circuit under load, but is used in connection with appropriate oil switches as an auxiliary disconnecting switch for maintaining the circuit open, even should the oil 25 switch be accidentally closed. Any suitable device may be associated with the operating crank 40 to lock it in open switch position if desired, so that the line may not be closed 30 without authority when current on the line would endanger the lives of workmen, or for other reason.

It will be readily understood that the particular construction shown is merely an illustrative embodiment of the underlying thought, and is not to be regarded as a limiting indication of what I claim as my 35 invention.

I claim—

1. A switch for high voltage lines comprising a post insulator having at its lower end a tapped pin, a switch contact base having a threaded boss adapted to screw into said tapped post, together with a corona hood and a cable terminal clamped between the contact base and the insulator pin by the engagement of the contact base with the pin. 45

2. In a switch for high voltage lines, a post insulator having a cap tapped in its upper surface, a switch contact member having a boss threaded to engage the insulator cap, a cable terminal clamped beneath the base of the contact element, and an arcing ring carried by the cap and surrounding 50 said contact and projecting beyond the free end thereof. 55

3. A switch for high voltage lines comprising a pair of substantially vertical and aligned multi-unit post insulators, a supporting structure to which the upper end of one unit is fixedly attached, a vertically reciprocating support aligned with the insulators and to which the lower end of the other multi-unit post is fixedly attached, 60 cooperating contacts at adjacent ends of said multi-unit insulators, means for attaching cable ends directly to the contact elements, and means spaced from the cable end attached to the vertically movable contact to maintain the freely swinging cable end clear of supporting structure. 65 70

In testimony whereof I have signed my name to this specification.

RICHARD H. MARVIN.
